UNITED STATES PATENT OFFICE.

SAMUEL ROYLANCE, OF NEW BEDFORD, MASSACHUSETTS.

POTATO PEELING AND WASHING MACHINE.

Application filed September 7, 1921. Serial No. 498,957.

To all whom it may concern:

Be it known that I, SAMUEL ROYLANCE, a citizen of the United States, residing at New Bedford, in the county of Bristol and State of Massachusetts, have invented certain new and useful Improvements in Potato Peeling and Washing Machines, of which the following is a specification, reference being had to the accompanying drawings.

This invention relates to potato peelers and washers and one of the principal objects of the invention is to provide a simple and efficient device of this type whereby quantities of potatoes may have their skins removed rapidly and effectively and the potatoes thoroughly washed so that all skins, dirt and foreign matter are removed within a minimum space of time.

A further object of the invention is the provision of a machine of this character in which all of the parts may be readily removed one from the other so that all parts may be thoroughly cleansed to keep the machine in a perfectly sanitary condition.

Further objects of the invention will appear as the following specific description is read in connection with the accompanying drawings which form a part of this application and in which:

Figure 1 is a front elevation;

Figure 2 is a side elevation;

Figure 3 a top plan view with the hopper cover removed;

Figure 4 a vertical sectional view taken centrally through the machine; and

Figure 5 a detail vertical sectional view showing the method of producing the abrading projections.

Referring more particularly to the drawing, C generally represents the casing and T the top thereof which, as shown in Figure 4, is provided with a depending flange 1 to engage within the upper section of the casing C. As shown in Figure 4, the casing C is constructed of independent sections 2 and 3 both tubular in form and preferably constructed of sheet metal of suitable gauge which is treated to prevent corrosion in any preferred manner, for instance, such as galvanizing. The lower section has a bottom 4 and secured thereto and projecting laterally therethrough are a plurality of lugs 5 through which attaching means are passed for securing the machine to the floor or other available support. The upper sec-

tion 3 of the casing is, as shown in Figure 4, provided with an inwardly and downwardly extending annular flange 6 adapted to enter the upper end of the section 2 so as to hold the sections 2 and 3 in proper aligned position and support the section 3 upon the upper edge of the section 2.

Secured to the bottom 4 centrally thereof is a step bearing 7 and mounted in this bearing is the end of a driven shaft 8 extended upwardly to a point slightly above the upper edge of the section 2 where it has removably keyed thereto a potato supporting base 9 circular in outline to conform to the inner contour of the casing and which is provided with abrading projections 10, the construction of which will hereinafter be described. The upper end of the shaft, as shown in Figure 4, is mounted in a cross bar or spider 11 which carries a bearing 12 coacting with a similar bearing 13 to support a drive shaft 14 in a position horizontal or at right angles to the driven shaft 8. The shaft 14 carries at one end a belt pulley 15 which may be connected to any suitable source of power and at the inner end the shaft 14 has secured thereto a toothed pinion 16 which meshes with a correspondingly toothed beveled gear 17 keyed to the shaft 8 by a set screw 18 or in any other suitable manner.

Removably secured within the upper section 3 in spaced relation thereto but concentric with the interior of the section is an abrading cylinder 19 provided with the abrading projections 20 similar to the projections 10 on the base 9 which are adapted to be engaged by the potatoes to remove the skin and dirt therefrom, as will be presently described. The upper section 3 is provided with a door 21, closing an opening 22 formed in the casing, and this door carries a spaced section which is removably attached to the door and provided with abrading projections similar to those indicated at 10 and 20. This section 23 fills an opening 24 formed in the abrading cylinder 19 so as to make the cylinder continuous during the operation of peeling and skinning the potatoes. The door is latched in closed position by a pivoted latch member 25 engaging a suitable keeper 26 on the side of the section 23. Secured to the casing immediately adjacent the door 21 and partially surrounding the door opening is a chute 27 into which the potatoes are discharged after

being properly peeled and washed. From the chute the potatoes may be discharged into any suitable receptacle such as a cooking vessel or the like.

- 5 In order to properly wash the potatoes I provide a movable spray head 28 which may be directed into the flared upper end 29 of the top T during the time that the potatoes are being peeled so as to wash all 10 skins and dirt therefrom through the openings formed in the abrading projections and between the bottom of the abrading cylinder and the potato supporting base 9. I also provide a second flexibly connected 15 nozzle 30 by which a stream of water may be directed into all parts of the abrading cylinder and associated parts to thoroughly cleanse them of any accumulated skins or dirt.
- 20 In order that the water utilized to wash the potatoes may not have access to the gears, I provide a receiving pan 31 having an annular peripheral flange 32 which has a lateral extension 33 arranged to overhang 25 the upper edge of the section 2, as clearly shown in Figure 4. In position, this pan 31 is supported immediately below but spaced away from the revolving base 9 and is centrally apertured, as indicated at 30 34, to receive the shaft 8. The pan is also provided with a discharge spout 35 which may be connected to the sewer in any suitable manner, or may discharge the wash water into any suitable receptacle, as is 35 found most desirable.
- As shown in Figure 5, I form the abrading projections 10 and 20 on the revolving base 9 and cylinder 19 by punching up the metal to produce crater like projections 40 36 having central apertures 37 and annular roughened edges 38 which effectively act upon the potatoes to remove skins, dirt and any foreign matter which may adhere thereto.
- 45 In the operation of the device, a quantity of potatoes are dumped into the flared upper end 29 of the top T falling upon the revolving base 9 which is continuously revolved through the medium of the shaft 14, 50 shaft 8 and associated gears. The potatoes on the revolving base 9 are rapidly turned over and thrown by centrifugal action into

engagement with the abrading projections on the cylinder 19 where they are further acted upon by the projections 20 to remove 55 all skins and foreign matter. During this operation or immediately following the same, as is found most desirable, but preferably while the potatoes are in motion, the spray from the nozzle 28 is discharged 60 on to the potatoes with such force as to effectively wash all particles of skin and dirt removed from the potatoes by the abrading projections through the openings 65 37 and through the space between the lower end of the cylinder and the revolving base into the pan 31 from whence they are discharged through the nozzle 35 into a receptacle or sewer as may be found desirable.

70 It will thus be seen that I have provided a very simple and efficient machine whereby large quantities of potatoes may have their skins and foreign matter removed therefrom in an effective and rapid manner, thus making the machine a very desirable adjunct to hotel kitchens and like places where large quantities of potatoes are peeled and washed at one time.

75 What I claim is:

80 In a potato cleaning machine, a casing constructed of upper and lower separable tubular sections, the upper section having a flange extending into the upper end of the lower section, abrading means arranged in the upper section and including a revolving supporting and abrading disk, a vertical shaft arranged in the lower section and engaged with said disk to rotate the same, 85 means carried in the last named section for rotating the shaft, and means arranged intermediate the sections for preventing particles removed from the potatoes from contacting with the operating means including a pan having an annular peripheral flange slidably fitting the interior of the upper end of the lower section, said flange having at its outer end a lateral extension 90 overhanging the lower edge of the upper section, the interior of said flange slidably receiving the flange of the upper section.

95 In testimony whereof I hereunto affix my signature.

100 SAMUEL ROYLANCE.
